W. H. WEHRENBURG
OIL OR GREASE GUN.
APPLICATION FILED JUNE 1, 1912.

1,040,476.

Patented Oct. 8, 1912.

UNITED STATES PATENT OFFICE.

WILLIAM H. WEHRENBERG, OF WEST SALEM, WISCONSIN.

OIL OR GREASE GUN.

1,040,476.

Specification of Letters Patent. Patented Oct. 8, 1912.

Application filed June 1, 1912. Serial No. 700,937.

To all whom it may concern:

Be it known that I, WILLIAM H. WEHRENBERG, a citizen of the United States, residing at West Salem, in the county of La Crosse and State of Wisconsin, have invented a new and useful Oil or Grease Gun; and I do hereby declare the following to be a full, clear, and exact description of the invention, such as will enable others skilled in the art to which it appertains to make and use the same.

This invention relates to a new and useful combined hand oiler or grease gun.

It is the principal aim of this invention to provide a device of this nature, adapted mainly for oiling or lubricating inaccessible parts of machinery, or other parts disposed at considerable heights, such as the machine parts of a wind mill and the like, and to obtain this result there has been devised a novel form of oiler or grease gun having a nozzle constructed of replaceable telescopic sections, which are connected together by threaded bands or the like, thereby enabling a machinist, or the owner of a wind mill or other machinery or the like, to reach inaccessible machine parts at considerable heights.

One of the features of the invention is the provision of a novel means for operating the plunger for feeding the oil or grease to the extensible nozzle.

Another feature of the invention is the provision of a handle, which is movable annularly about the circumference of the can, thereby enabling the operator to move the handle with relation to a lever of the operating mechanism of the plunger, in order that the operator may conveniently hold the gun when manipulating the same.

The invention comprises further features and combination of parts, as hereinafter set forth, shown in the drawings and claimed.

In the drawings:—Figure 1 is a view in perspective of the improved oil or grease gun constructed in accordance with the invention. Fig. 2 is a vertical sectional view through the can, showing the plunger therein in its normal position, prior to forcing the oil or grease through the nozzle. Fig. 3 is a sectional view on line 3—3 of Fig. 1.

Referring more particularly to the drawings 1 designates the oil or grease can or receptacle, the top of which is provided with an opening 2 (which is closed by means of

a plug 3) through which the oil or grease may be deposited in the can.

Adapted to be moved in the direction of the arrow *a* to force the oil or grease through the nozzle 4, is a plunger 5, to which the plunger rod 6 is connected by threads, as shown at 7. This plunger rod 6 operates through a packing or stuffing box 8, in the bottom of the can or receptacle. A spring 9 is interposed between the plunger 5 and the stuffing box, which assists in forcing the plunger in the direction of the arrow *a*.

Connected to the lower end of the plunger rod 6 as at 10 is one end of a lever 11, the substantially central portion of which is fulcrumed as at 12 to a link 13, which in turn is pivoted at 14 between the two ends 15 of the band 16, which is annularly movable in the groove 17 adjacent the lower portion or bottom of the can or receptacle. In this manner the operating mechanism of the plunger may be adjusted relatively to the handle 18, thereby enabling an operator to conveniently manipulate the gun. The free end of the lever 11 terminates in a handle 19, whereby the same may be operated. Not only the operating mechanism is adjustable annularly with relation to the can and the handle 18, but may be held in a fixed position with relation to the can, by tightening the screw 20, which is threaded into the end portions 15 of the band 16. The handle 18 is also movable with relation to the can and the operating mechanism of the plunger.

To obtain this result the bands 21 and 22 are slidably annularly about the can, the band 21 moving in the groove 23 in order to prevent downward displacement of the same. The portions 24 of the handle 18 are secured or riveted between the ears or end portions 25 and 26 of the bands 21 and 22, by means of the rivets 27 and 28. The groove 17, in which the band 16 annularly slides prevents upward movement of the band 16.

The nozzle 4 is constructed of a plurality of telescopically united sections 29, firmly held in position with relation to one another by the threaded band 30, in the manner shown in Fig. 3. The lower section 29 is threaded into an extension 31 of the top of the can, as shown. The upper section 32 of the nozzle is curved laterally, as shown in Fig. 1, in order that an operator may lubricate inaccessible machine parts, and owing to the fact that the number of sections 29 of

the nozzle may be increased or decreased, the nozzle may be shortened or increased in length, so that the operator may reach the machine parts at considerable heights.

5 From the foregoing it will be noted there has been devised a novel, desirable and convenient oil or grease gun, and one which has been found particularly practical.

The invention having been set forth, what 10 is claimed as new and useful is:—

An oiler or grease gun comprising a can having a nozzle, a plunger operable in the can, an operating mechanism therefor hav-

ing adjustable connections with the can, the can having an annular groove adjacent its top, a band slidable in the groove, a second band slidable annularly about the can below the groove, and a handle connected to the bands.

In testimony whereof I have signed my name to this specification in the presence of two subscribing witnesses.

WILLIAM H. WEHRENBERG.
